UNITED STATES PATENT OFFICE.

WILLIAM H. FYE, OF CHICAGO, ILLINOIS, ASSIGNOR OF ONE-HALF TO
CHARLES AVERY, OF SAME PLACE.

SASH-HOLDER.

SPECIFICATION forming part of Letters Patent No. 394,352, dated December 11, 1888.

Application filed September 10, 1888. Serial No. 285,028. (Model.)

To all whom it may concern:

Be it known that I, WILLIAM H. FYE, a citizen of the United States, residing at Chicago, in the county of Cook and State of Illinois, have invented a new and useful Window-Tightener, of which the following is a specification.

My invention relates to contrivances for tightening windows; and it consists of two narrow metal plates, one to be screwed fast to the stop-bead of a window-frame, at the edge of the same next to the sash, and made with flanges at its edges extending in opposite directions, and a hole somewhat above its middle point for the passage of a rivet, the other with a slot made lengthwise for the passage of such rivet, a flange on its outer edge, and a thumb-piece on its broader end. The construction and application of such contrivance are illustrated in the accompanying drawings, in which—

Figure 1 is an elevation of a portion of a window frame and sash embodying my invention. Fig. 2 is a cross-section of the same, taken on the line 1 1 of Fig. 1. Fig. 3 is a detail plan section of the same, taken on the line 2 2 of Fig. 2. Fig. 4 is an edge elevation of my tightener detached. Fig. 5 is a front elevation of the same. Fig. 6 is a similar view showing the wedge part in a lowered position as compared with Fig. 5.

Similar letters refer to similar parts throughout the several views.

In the drawings, A is a plate screwed fast to the stop-bead C next to the sash C'. It is made with the flanges A' and A² at its edges, extending at right angles to the plate, but in opposite directions. The edges of the plate make a small angle to each other. The flange A' passes between the stop-bead and the sash, and thus aids the screws a in holding the plate firmly in position.

B is a rivet passing through the plates A and D, but leaving a space between its head and said plates sufficient to permit the plate D to be received therein with room enough to move freely.

D is a wedge-shaped plate made to fit tightly between the flange A² and the sash C'. This plate is made with the flange A³ extending at right-angles from the edge next the sash and

curved slightly inward at its extremity next to the narrower end of the plate. The edge of the plate next to the flange A² is in a straight line throughout its entire length. This flange is designed to prevent the plate from wearing a groove in the sash and to aid in holding the sash firm when tightened. The plate D has a slot, D³, running lengthwise parallel with the flange A² when the sash is tightened by the action of the plate. Through this slot the rivet B passes, the slot being made of such width as to permit the plate D to slide up and down. At its lower end the plate D is provided with a thumb-piece, D². The plates are secured to the stop-bead C a little distance below the middle rail, c, so that the lower sash, C', when pressed by the plate D, will force the upper sash, C², against the window-box; and thus both sashes be tightened. The plates are placed with their narrower ends upward, and a pair of plates is secured to each stop-bead.

The manner of using the tightener is obvious. The plates being secured, as above indicated, the thumb and finger are applied to the piece D² and the plate D is forced upward. Owing to its wedge-like shape, it will, as it moves, press the lower sash more and more tightly against the upper sash, and that against the window-box, and thus tighten both without absolutely locking them.

My invention is not intended to be a window-fastener—neither lock nor support. It is designed to tighten windows, so as to prevent rattling and to shut out dust, noise, smoke, cold air, &c., and to secure sash against moving when weights and windows are not perfectly balanced.

Having now described my invention, what I claim as new, and desire to secure by Letters Patent of the United States, is—

In a sash-securer, the combination of the base-plate A, with its flange A² at right angles to the plane of the same, the plate D, with its flange A³, with slot D³ parallel to the flange A², and thumb-piece D², and the rivet B, secured in the plate A, all substantially as set forth.

WILLIAM H. FYE.
